ATTACHMENT-PLUG FOR ELECTRIC CIRCUITS.

1,080,327.

Specification of Letters Patent.

Patented Dec. 2, 1913.

Application filed March 21, 1913. Serial No. 755,909.

To all whom it may concern:

Be it known that we, FRANK H. CHAPMAN and OWEN E. KENNEY, citizens of the United States, and residents of Toledo, in the county of Lucas and State of Ohio, have invented a certain new and useful Attachment-Plug for Electric Circuits; and we do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to electrical devices, and particularly to the plug members of the quick connecting type of plug and socket couplings for electric circuits, but is not restricted to such use as it may be used in any connection for which it may be adapted or appropriate.

The object of our invention is the provision of a simple and efficient plug member for couplings of this character, which is provided with improved means for retaining the relatively movable plug parts in assembled relation and for coöperating with the plug parts and the threaded or otherwise suitably formed lining of a socket member to retain the two coupling members of a coupling of this nature in coupled relation.

The invention is fully described in the following specification, and while, in its broader aspect, it is capable of embodiment in numerous forms, a preferred embodiment thereof is illustrated in the accompanying drawings, in which,—

Figure 1 is a side elevation of a coupling embodying the invention with the plug member and a portion of the socket member in central longitudinal section, the section of the plug member being on the lines x , x in Fig. 3. Fig. 2 is a different side elevation thereof with portions of the coupling members broken away. Fig. 3 is an end elevation of the plug member of the coupling. Fig. 4 is an inner end view of the plunger part of the plug member, and Fig. 5 is a fragmentary view of the socket and plug members with such members in engaged position.

Referring to the drawings, A designates the socket member of the coupling, which member is of customary or any suitable con-

struction, and has the central contact part 1 and the spirally grooved or threaded lining 2 forming the other contact of the socket.

The plug member B of the coupling in which the features of our invention reside, comprises the body part 3 and the plunger part 4, which latter is mounted for axial reciprocatory movements in a longitudinally extending socket 5 in one end of the body part 3. A coiled compression spring 6 is disposed in the base of the socket 5 and acts upon the plunger 4 to cause its outer end to be yieldingly projected a short distance without the open end of the socket 5, as shown in Figs. 1 and 2. A ferrule 7 of metal or other suitable electrical conductive material is fitted around the outer end portion of the body part 3 to provide a surface for contact with the lining of the socket member A when the plug is inserted therein. The plunger 4 has a recess 8 in one side thereof from which a spring contact finger or brush-member 9 projects with its outer end working in a registering longitudinal recess 10 in the wall of the plug socket 5 in sliding contact with the ferrule 7, which closes the outer side of the recess 10. The brush part 9 is clamped to the plunger by a screw 11, or in any other suitable manner, and has connection with the terminal of one of the lead-in wires 12 and 13, the other of said wires passing, in the present instance, through a hole 14 in the plunger and connecting to a center contact part 15 at the outer end of the plunger, such contact part 15 being in position to make contact with the part 1 of the socket member when inserted therein.

In carrying out the feature of our present invention a dog or catch-member 16 is mounted in a longitudinally disposed recess 17 in one side of the plunger 4 being pivoted therein, as at 18, and extends from its pivot toward the inner end of the plunger and thence outwardly into an opening 19 in the wall of the plug socket 5. The dog 16 is of hooked shape and is adapted to coact with the outer side wall of the opening 19 to limit the outward or spring influenced movements of the plunger relative to the body part 3 of the plug, as shown in Fig. 1. Upon a compression of the plunger 4 within the socket 5 the outer or free end of the dog 16 is caused to work outwardly through the opening 19, under the influence of a spring

20, and to project beyond the outer side of the socket wall a sufficient distance to adapt it to coat with a registering thread groove in the lining 2 of the socket member A, should the plug member be disposed therein, as shown in Fig. 5, thus holding the two members of the coupling in coupled engagement. The dog 16 having engaged the socket threads a slight turn of the plug member in clock-wise direction will cause a firm contacting of the contact parts 1 and 15 due to the outer end of the dog turning in the thread groove of the socket lining.

It is evident from the above that the dog 16 performs a dual function, first to engage within the opening 19 to coöperate with the outer wall thereof to retain the plug parts 3 and 4 in assembled relation, and to limit the outward spring influenced movements 20 of the plunger; and, secondly, to provide a part which is automatically operable to engage the threaded lining of the socket member of a coupling upon a compression of the plunger 4 within its plug socket when the plug is inserted into a socket member. It is, of course, understood that the compression of the plunger 4 within the plug part 3 occurs upon an insertion of a plug member into a socket member, when the 30 plunger contact part 15 has contact with the socket part 1 and the inward movement of the plug part 3 is continued for a short distance relative to the plunger. The electrical contacts between the plug and socket members are made between the parts 1 and 15 and between the socket lining 2 and ferrule 7 of the plug so that the dog 16, in the 35 present instance, does not serve as one of the contact members.

40 It is apparent that to remove the plunger 4 from the plug socket, it is only necessary to insert a pointed instrument or object into the opening 19 to depress the dog 16 sufficiently to release its engagement with the outer side of the opening wall, as the spring 45 6 will then act to force the plunger out of the socket.

We wish it understood that our invention is not limited to any specific construction or arrangement of the parts except in so far as such limitations are specified in the 50 claims.

Having thus described our invention, what we claim as new, and desire to secure by 55 Letters Patent, is,—

1. A plug of the class described having two relatively movable sections, and means carried by one of said sections and serving to limit the relative movements of the sections in one direction and automatically operable to project without the sections to form a thread engaging part when the sections are relatively moved in the opposite direction.

65 2. In combination, a socket member, a

70 plug for fitting into said member and having two relatively movable sections, and means carried by one of said plug sections and serving to limit the relative movements of the plug sections in one direction and automatically operable, upon a relative movement of the plug sections in the opposite direction when inserted into the socket member, to project without the sections and have holding engagement with the interior side 75 wall of the socket member.

3. A plug of the class described comprising a socketed member having an opening in its side wall and a plunger reciprocally movable in said member and having a side 80 recess in register with said opening, a pivoted part mounted in said recess and having a laterally projecting end portion normally projecting into said opening to coat with a wall thereof to limit the relative outward movements of said member and plunger, and means for influencing an outward movement of the free end portion of said part whereby it is caused to work outwardly through said opening to form an external thread engaging part when the plunger is moved from normal position into 85 said member.

4. A plug of the class described having relatively movable telescoping sections the 95 outer of which has an opening in its wall, a member pivotally carried by the inner section and normally coöperating with the outer section to limit the relative movements of the sections in one direction and having 100 its free end laterally angled to adapt it to project into said opening, and means influencing an outward movement of the free end of said member through said opening to form an external thread engaging part when 105 one section is moved a predetermined extent within the other.

5. In combination, a socket member, a plug for fitting into said member and having two sections mounted for relative longitudinal movements, and means carried by one of said plug sections and coacting with the other section to limit the relative outward movements thereof and automatically operable by a predetermined relative inward 110 movement of the plug sections to engage the inner side wall of the socket member to retain the plug and socket member in assembled relation when the former has been inserted a predetermined extent into the latter. 115

6. A plug of the class described having relatively movable telescoping sections the outer of which has an opening in its wall, an L-shaped member pivotally carried by the inner section with one end projecting 120 into said opening to coat with a wall thereof to limit the relative outward movements of the sections, the end of said member which projects within said opening being shaped to adapt it to project through and 125 130

without the opening to form an external
thread engaging part when the sections have
relative inward movements, and means act-
ing on said member to influence an outward
5 movement of the free end thereof through
said opening.

In testimony whereof, we have hereunto

signed our names to this specification in the
presence of two subscribing witnesses.
